(57) **CLAIM**

The ornamental design for a vaginal manipulator, as shown and described.

DESCRIPTION

FIG. 1 is an isometric view of a vaginal manipulator showing a head attached to a handle with a door located on a bottom side of the head. The door being in a closed position.

FIG. 2 is a left side view of the vaginal manipulator illustrated in FIG. 1.

FIG. 3 is a right side view of the vaginal manipulator illustrated in FIG. 1.

FIG. 4 is a top view of the vaginal manipulator illustrated in FIG. 1.

FIG. 5 is a bottom view of the vaginal manipulator illustrated in FIG. 1.

FIG. 6 is a front view of the vaginal manipulator illustrated in FIG. 1.

FIG. 7 is a back view of the vaginal manipulator illustrated in FIG. 1; and,

FIG. 8 is an isometric view of the vaginal manipulator illustrated in FIG. 1 showing the door in an open position.

The broken lines shown in FIGS. 1-8 illustrate portions of the vaginal manipulator that form no part of the claimed design.

1 Claim, 6 Drawing Sheets
